UNITED STATES PATENT OFFICE.

SAMUEL RUBINSTEIN, OF KENILWORTH, NEW JERSEY.

DESIGN FOR A MOUNT FOR A PICTURE.

56,627.

Specification for Design.

Patented Nov. 16, 1920.

Application filed June 13, 1919. Serial No. 304,066. Term of patent 3½ years.

To all whom it may concern:

Be it known that I, SAMUEL RUBINSTEIN, a citizen of the United States, residing at Kenilworth, in the county of Union and State of New Jersey, have invented a new, original, and ornamental Design for a Mount for a Picture, of which the following is a specification, reference being had to the accompanying drawing, forming part thereof.

The figure is a face view of a mount, showing my new design, the same having a space intended to receive a picture.

I claim:

The ornamental design for a mount for a picture, as shown.

SAMUEL RUBINSTEIN. [L. S.]
